UNITED STATES PATENT OFFICE.

WILLIAM H. WAREHAM, OF WASHINGTON, DISTRICT OF COLUMBIA.

LIFE-RAFT-RELEASING MECHANISM.

1,197,413.

Specification of Letters Patent. Patented Sept. 5, 1916.

Application filed December 6, 1915. Serial No. 65,389.

To all whom it may concern:

Be it known that I, WILLIAM H. WAREHAM, a citizen of the United States, residing at Washington, in the District of Columbia, have invented certain new and useful Improvements in Life-Raft-Releasing Mechanisms; and I do hereby declare the following to be a full, clear, and exact description of the invention, such as will enable others skilled in the art to which it applies to make and use the same.

This invention relates to a life raft releasing mechanism.

It is a matter of common knowledge that life rafts which are ordinarily disposed on the decks of boats are secured to the decks by means of hooks or other suitable securing means which must necessarily be manually operated to release the rafts. It is of course necessary to secure the rafts in place inasmuch as they would otherwise shift with the raising or lowering of one side or the other of the boat. The securing of the rafts to the decks or other supporting means by mechanism which must be manually operated to release the rafts has been found particularly disadvantageous inasmuch as their use is only necessitated at times of distress and at such times there is a tendency for the persons on the boat to rush to the life boats and neglect to release the rafts. The result is that when the boat sinks the rafts will be carried with it and consequently will be of no value in saving lives of persons who have not been fortunate enough to reach the life boats.

It is therefore an object of my invention to provide mechanism for securing the rafts to their supports which will be automatically operated to release the rafts upon the passing of the supports beneath the surface of the water.

It is a further object of my invention to so construct the device that its structure and operation will be simple so that it will not fail to function properly when the necessity arises.

With these and other objects in view, such as will appear as my description progresses, my invention comprises the combination and arrangement of parts as set forth in and falling within the scope of the appended claims.

In the drawings: Figure 1 is a side elevation of a conventional form of raft showing my mechanism attached thereto and in its

securing position; Fig. 2 is a plan view of the same; Fig. 3 is a perspective view of the fastener at one end of the raft showing the same in its securing position, Fig. 4 is a similar view after the raft has been released, Fig. 5 is a sectional view of the flange on the base plate.

Referring to the drawing by reference characters wherein like parts are indicated by like characters throughout the several views: For the sake of convenience of illustration and description, I have shown a conventional form of raft but it is to be understood that the mechanism may be applied to various forms of rafts in use. This raft 1, as shown, is supported on a deck 2 by means of rails 3.

In order that the raft may be secured in place in such manner that it will be automatically released upon its passing below the surface of the water, I have provided a pair of bars 4 which have integral eyes 5 thereon and which are secured to the ends of the raft by suitable fasteners 6, the fasteners being shown in the present case as flexible members passing through the eyes 5. A plate 7 is secured to the deck by means of suitable bolts 8 adjacent each end of the raft and each of these plates is provided with a flange 9 beneath which one end of the adjacent bar 4 is adapted to engage. The plates are further provided with upwardly extending abutments 10 which are in spaced relation to the flanges 9 and between which and the flanges the bars 4 are located. The ends of the bar 4 are rounded, at 11, to facilitate their disengagement from beneath the flanges 9. These flanges 9 are provided with downwardly extending wings 12 to prevent the lateral movement of the bars 4. The plates 7 are further provided with wings 13 between which pawls 14 are pivoted. The bills of these pawls 14 are adapted to extend into sockets 15 in the adjacent end of the bars 4. These pawls are maintained in this position by means of latch members 16 which are pivoted, at 17, between the wings 13. The ends of these latch members 16 engage shoulders 18 upon the pawls 14 and are provided with anti-friction rollers 19.

In order that the latch members may be disengaged from the pawls, I have provided rods 20 which extend through and are pivotally mounted in the wings 13, the portions of the rods located between the wings form-

ing the pivots of the latch members, the latch members being secured to these portions. A float 21 is secured to the end of each of these rods 20 and is adapted to move 5 the rod pivotally. The latch members 16 are so arranged that when the rods 20 lie parallel with the deck and the floats are in their lowered positions, the ends of the latch members will engage the shoulders on the 10 pawls. The raft will thus be held in a predetermined position as long as the floats are in their lowered positions. When the raft passes below the surface of the water the 15 floats will move upwardly relative to the plates 7 and the latch members will be disengaged from the shoulders on the pawls, being facilitated in this movement by the antifriction rollers in the ends thereof. When the latch members are disengaged 20 from the pawls, they will be free to rotate about their pivots to release the bars 4. As the raft rises from the deck of the boat the bills of the pawls will be disengaged from the bars and the ends of the bars will move 25 from beneath the flanges 9, this movement being permitted because of the fact that the ends of the bars are rounded, at 11, as previously described and further because of the fact that the bars are loosely connected to 30 the raft.

Without entering into a detailed description or enumeration of the advantages of my device it will be obvious that I have provided a device for securing a raft to its supporting means on a boat in such manner that should the raft pass beneath the surface of the water with the boat it will be automatically released so that it may rise to the 35 surface irrespective of the position of the boat.

While I have illustrated and described a particular embodiment of my invention, it has merely been for the sake of convenience and I do not wish to be limited to that particular embodiment as it is obvious that numerous changes may be made in the details 45 of construction without departing from the

spirit of the invention or exceeding the scope of the appended claims.

What I claim is:—

1. In a mechanism of the class described, the combination with a bar carried by a life raft, of means for engaging the same to maintain the raft in a predetermined position and automatically operated means for releasing the aforementioned means, the aforementioned bar being released from the engaging means by the upward movement of the raft. 50

2. The combination with a life raft, of 60 bars on the ends thereof, plates having flanges thereon for engaging one end of the bars, pawls for engaging the other end of the bars to retain the raft in a predetermined position and automatically operated 65 means for releasing said pawls, the said bars being disengaged from the flanges by the upward movement of the raft. 70

3. The combination with a life raft, of a bar carried thereby, a plate adapted to be 70 secured to the deck of a boat and having a flange disposed parallel thereto, the flange being adapted to engage one end of the bar and having means thereon for preventing the lateral movement of the bar, a pawl 75 adapted to engage the other end of the bar, a latch for said pawl and automatically operated means for releasing the latch. 80

4. The combination with a life raft having a bar loosely mounted on one end thereof, a plate adapted to be secured to the deck of a boat adjacent the end of the raft and having a flange thereon, the said bar being adapted to extend beneath said flange, a pawl pivoted on the plate and adapted to 85 engage the bar, a latch mounted on the plate for engaging the pawl and a float for disengaging the latch from the pawl. 80

In testimony whereof, I affix my signature, in the presence of two witnesses.

WILLIAM H. WAREHAM.
